DISPENSING TOP FOR POWDER HOLDERS

William J. Bauer, New York, N. Y., assignor to
Robert Lederfeind, New York, N. Y.Application August 3, 1934, Serial No. 738,267
Renewed August 28, 1935

8 Claims. (Cl. 132—82)

The invention relates to holders for retaining powder or similar material in loose form, and more particularly to the closure element or top associated therewith and through which the retained powder is to be dispensed.

The invention has for an object the provision of a simple and effective closure member of this nature which may not only serve for convenient removal of the powder from the container but will enable such closure member or top to be readily applied to the open end of the container and to secure a proper closure therat.

A further object of the invention resides in the provision of a closure member which may be inexpensively constructed and which is readily manipulated in the dispensing of the container contents; and when not in use serves adequately to prevent spilling of the powder contents.

Still another object of the invention resides in the provision of a closure member adapted for use with a container element constituted of elastic material, and requiring no cements or adhesives for securing the member thereto.

In the accompanying drawings, which illustrate the invention in several of its preferred embodiments, Fig. 1 is a part elevation and part vertical section illustrating the novel closure member as applied to a powder container.

Fig. 2 is a plan thereof, with cover removed. Figs. 3 and 4 are plan views respectively of the cover element and of one of the clamping plates.

Figs. 5 and 6 are similar views respectively of the associated clamping plate and of a screen held therebetween.

Fig. 7 is a part front elevation and part vertical section illustrating a modified form of the closure member.

Fig. 8 is a plan thereof.

Figs. 9 and 10 are plan views of the associated closure elements, the element shown in the latter view also constituting one of the clamping elements; and Figs. 11 and 12 are plan views respectively of the other of the associated clamping elements and of a screen held therebetween.

Referring to the drawings, 10 designates a container for powder, said container being preferably of the nature of a loader element designed to be fitted within a cylindrical box 11 or other receptacle. It is preferred to construct this container of elastic material and in the form more or less of a bellows, for example as is more particularly set forth in my Patent Number 1,999,227, April 30, 1935.

The container as thus disclosed is constituted 55 of elastic or resilient material, such as rubber,

and is of the desired contour and preferably provided with a series of circumferential corrugations or folds 12 forming a bellows or like collapsible member thereof.

In accordance with the present invention, provision is made for securing to the uppermost fold 13 of the container a closure member constituted of a pair of metal clamping elements or plates between which the fold 13 may be securely held.

Thus, a clamping plate or annular disk 15 is associated with a similar clamping plate 16, and each plate provided with an aperture 17 and 18, respectively, adapted to register when the plates are superposed for the purpose hereinafter set forth. The plate 15, furthermore, is provided with a depressed seat or inwardly extending flange 19 designed to receive a screen or strainer 20, this screen being held in place firmly by a depressed inwardly extending flange 21 of the plate 16 resting thereon when the plates are superposed, as indicated in Fig. 1 of the drawings.

In this position, also, the two said plates are designed to receive and hold between them the inner edge or fold 13 of the container, and the union is insured by turning under the said fold a plurality of outwardly extending and bendable spurs or tabs 22 extending outwardly from the edge of the uppermost plate 16. These tabs are bent over and clamped tightly toward the uppermost plate to compress or pinch the said edge of the resilient material constituting the container with sufficient force to prevent normally removal of the said plates which thus form a supporting frame for a closure element which may be variously constituted.

For example, as indicated in Fig. 1 of the drawings, the cover element 26 designed for closing the aperture 18 is constituted as a circular disk 27 having an upper rim or flange 28, the disk being adapted to seat on the flange 21 with its flange 28 overlapping. The said flange 28, furthermore, is hinged to the outer end 29 of a bar 30 adapted to extend diametrically over the outer face of the disk, the said bar being hinged at its opposite end 31 to the annular superposed plate 16 and thus attaching the said cover element thereto.

When the disk or cover element 27 is seated in position to close the aperture 18, the end 29 of the bar, or rather the hinge, is adapted to be held by a catch 32 of the plate 16 to retain the cover element in position for closing said aperture. By releasing the catch, the cover will be swung

upwardly with the bar under the action of a spring 33 to permit removal of the contents of container 10. As these contents are depleted and the container collapses toward the bottom 5 of the box 11, it will be evident that the cover element could not be swung back sufficiently to open fully the container because of the cylindrical shape of box 11; and it may then be swung about the end 29 of the bar (as indicated in the 10 dotted line position, Fig. 1) to bring it a sufficient height above the box wall to provide full access to the aperture 18.

In Figs. 7 to 12, a different form of closure is set forth, the same being of a more simple construction and embodying a pair of perforated plates or disks, the one plate 40 constituting the uppermost of the holding plates for the fold 41 of container 42 and a plate 43 the lowermost, as in the previous embodiment. This latter plate is 15 provided with an aperture 44 and with an inwardly extending flange 45 to provide a seat for screen 46.

Over the plate 40 is mounted a further perforated plate or disk 47, as by riveting the two plates together at the center 48 thereof with sufficient play for angular movement of the one on the other about said rivet as a center. These plates 40 and 47 are provided with respective 20 perforations 49 and 50, which are designed to register when the one plate is turned relatively to the other, as about the pivot 48, the limit of angular movement being determined, for example by a pin 51 extending upwardly from the plate 40 and into an arcuate slot 52 of the plate 25 47. In this embodiment the box or receptacle 53 surrounding the container 42 is substantially 30 square in cross-section.

I claim:

1. A closure for a powder container having a 35 top opening, said member comprising a pair of superposed plates having apertures through which the powder may be dispensed, and between which plates the edge of the container opening is located, the uppermost plate being provided with tabs extending therefrom and fitting under the underlying plate to clamp and hold the container material between said superposed plates.

2. A closure member for a powder container having a top opening, said member comprising a 40 pair of superposed plates having apertures through which the powder may be dispensed, and between which plates the edge of the container opening is located, the uppermost plate being provided with tabs extending therefrom and fitting under the underlying plate to clamp and hold the container material between said superposed plates, and means to temporarily close the apertures of said plates.

3. A closure member for a powder container 45 of rubber and having a top opening, said member comprising a pair of superposed plates having apertures through which the powder may be dispensed, and between which plates the edge of the container opening is located, the uppermost plate being provided with tabs extending therefrom and fitting under the underlying plate to clamp and hold the container material between said superposed plates, and means to temporarily close the apertures of said plates.

4. A closure member for a powder container 50 having a top opening, said member comprising a pair of superposed plates having registering apertures through which the powder may be dis-

pensed, and between which plates the edge of the container opening is located, the uppermost plate being provided with tabs extending therefrom and fitting under the underlying plate to clamp and hold the container material between said superposed plates, a cover element for closing temporarily the apertures of said plates and including a bar hinged at one end to the uppermost plate, a lid of a diameter greater than that of the aperture of said uppermost plate and 5 hinged to the outer end of the bar to fold thereunder, and a catch secured to the uppermost plate diametrically opposite the hinge of the said bar and adapted to hold its outer end to the said uppermost plate. 15

5. A closure member for a powder container having a top opening, said member comprising a pair of superposed plates having apertures through which the powder may be dispensed, and between which plates the edge of the container opening is located, the uppermost plate being provided with tabs extending therefrom and fitting under the underlying plate to clamp and hold the container material between said superposed plates, a screen carried by the underlying 20 plate over its aperture, and a movable cover element carried by the uppermost plate over its aperture. 25

6. A closure member for a powder container having a top opening, said member comprising a pair of superposed plates having apertures through which the powder may be dispensed, and between which plates the edge of the container opening is located, the uppermost plate being provided with tabs extending therefrom and fitting under the underlying plate to clamp and hold the container material between said superposed plates, and an oscillatable cover element carried by the uppermost plate, the latter and cover element having apertures adapted to co- 30 operate when said element is rotated. 35

7. A closure member for a powder container having a top opening, said member comprising a pair of superposed plates having registering apertures through which the powder may be dispensed, and between which plates the edge of the container opening is located, the aperture of the uppermost plate being constituted as perforations therein and said plate also being provided with tabs extending therefrom and fitting under 40 the underlying plate to clamp and hold the container material between said superposed plates, and a perforated cover element oscillatably secured upon said uppermost plate, the perforations of the said cover element being adapted 45 for registry with the perforations of said plate when the cover element is rotated. 50

8. A closure member for a powder container having a top opening, said member comprising a centrally apertured plate with depressed seat 55 bounding the aperture, a screen resting upon said seat, a centrally apertured cover plate with depressed seat adapted to fit within the seat of the apertured plate and to hold thereby the said screen thereto, the upper edge of the container 60 being located between the two said plates, and the cover plate being provided with tabs extending from its edges and turned under the first-named apertured plate to clamp and hold the container material between the superposed plates, 65 and a cover element for the aperture of the cover plate and movably mounted upon the latter. 70

WILLIAM J. BAUER.
